UNITED STATES PATENT OFFICE.

OTIS COOPER, OF MANCHESTER, ILLINOIS.

JAR-HOLDER.

SPECIFICATION forming part of Letters Patent No. 783,618, dated February 28, 1905.

Application filed October 29, 1903. Serial No. 179,086.

To all whom it may concern:

Be it known that I, OTIS COOPER, a citizen of the United States, residing at Manchester, in the county of Scott and State of Illinois, have invented certain new and useful Improvements in Jar-Holders; and I do declare the following to be a full, clear, and exact description of the invention, such as will enable others skilled in the art to which it appertains to make and use the same.

My invention relates to improvements in devices for holding jars and the like while their covers or closures are being applied or removed.

The object of my invention is to provide a device of this character which will be simple in construction, durable in use, very effective for the purpose intended, and comparatively inexpensive to manufacture.

With this and other objects in view the invention consists in certain novel features of construction, combination, and arrangement of parts, as will be more fully described, and particularly pointed out in the appended claim.

In the accompanying drawings, Figure 1 is a perspective view of my improved jar-holder. Fig. 2 is a horizontal sectional view through the same. Fig. 3 is a vertical sectional view taken on the line 3-3 of Fig. 2.

In the embodiment of my invention as illustrated in the drawings the numeral 1 denotes a base or bottom of such size and shape as that of the bottom of the jar, bottle, or other container which is placed upon it. As shown, it is circular and adapted to receive the ordinary cylindrical fruit-jar. Secured around the edge or periphery of said base at suitable intervals by screws or other suitable fastening means 2 are vertically-projecting clamping bars or fingers 3, which are adapted to engage the outside of the jar which rests upon the base 1. Said clamping-bars are further secured and held upon the base by a band or ring 4, which surrounds the bars and base, and is secured to

the periphery of the base between said bars by nails, screws, or other fastening means 5. Owing to this manner of connecting the lower ends of the clamping-bars to the base the bars will have a slight pivotal movement in planes

tangent to the periphery of the base in order that they may be more effectively adjusted upon the jar to be held. A flexible band 6, preferably of metal, surrounds and connects said clamping-bars, said band being secured to each bar adjacent to its upper end, as at 7. To the ends of said band, which are brought together at one of the spaces between two of the clamping-bars, are attached handles 8, which may be secured either by fastening the ends of the bands directly to the handles or by riveting said ends to plates 9, which are screwed to the handles, as shown in the drawings. The handles may be of any desired form, but are preferably coacting half-sections, as shown, being formed by cutting an ordinary tool-handle longitudinally into halves.

When the flat faces 10 of the handles to which the plates 9 are secured are brought together, the flexible clamping-band 6 will draw the clamping-bars into engagement with the outside of the jar or the like upon the base 1 and effectively hold the same. In order to increase the clamping power of said bars and to overcome the liability of breaking the jar by the application of too much pressure, I provide the inner face of each of the clamping-bars with a cushion 11 in the form of a narrow longitudinal strip of rubber or any other suitable material.

The use and advantages of my invention will be readily understood. The jar, bottle, or the like to be held is placed upon the base 1 within the clamping-bars 2, and the handles 8 are then grasped and drawn together to cause the band 6 to force the bars 2 into engagement with the jar to effectively hold the same while its screw cap or cover is being applied or removed.

It will be understood that the device may be made in various sizes to receive different-size jars and also in various shapes to adapt the same for use upon unusual-shaped containers. If so desired, the clamping-bars may be curved to conform to the shape of the side of the jar or they may be resilient or flexible, and thus adapt themselves to the jar. Various other changes in the form, proportion, and the minor details of construction may be

resorted to without departing from the principle or sacrificing any of the advantages of this invention.

Having thus described my invention, what I claim as new, and desire to secure by Letters Patent, is—

A device for holding jars and other vessels, comprising a base, upright clamping-bars spaced apart, arranged around the periphery of the base, pivots radial to the base, connecting the lower ends of the clamping-bars to the periphery of the base and adapting said clamping-bars for angular movement in planes

at right angles to said pivots, and a flexible annular band on the outer side of the said clamping-bars, near their upper ends, pivotally connected thereto, open at one side and having handles at its ends.

In testimony whereof I have hereunto set my hand in presence of two subscribing witnesses.

OTIS COOPER.
